PAGE 2

Fig. 4.

Fig. 5.

FIG. 1 is a top plan view of one form of a crewel yarn rack embodying my new design;

FIG. 2 is a front elevational view of the crewel yarn rack shown in FIG. 1;

FIG. 3 is a side elevational view of the crewel yarn rack shown in FIG. 1;

FIG. 4 is a perspective view of the crewel yarn rack shown in FIG. 1;

FIG. 5 is a perspective view of another form of a crewel yarn rack embodying my new design.

I claim:

The ornamental design for a crewel yarn rack, as shown.
